The ornamental design for a clothes hanger hook, as shown and described.

DESCRIPTION

FIG. 1 is a front elevational view of a clothes hanger hook showing my new design, the rear elevational view being the mirror image thereof;

FIG. 2 is a right side elevational view thereof, the left side elevational view being the mirror image thereof;

FIG. 3 is a top plan view thereof;

FIG. 4 is a bottom plan view thereof; and,

FIG. 5 is a perspective view thereof, with the dashed lines showing the outline of a jacket and hanger for illustrative purposes only and forming no part of the claimed design.
